UNITED STATES PATENT OFFICE.

JOHN STAUNTON KING, OF TORONTO, CANADA.

VENTILATED BOOT.

SPECIFICATION forming part of Letters Patent No. 556,825, dated March 24, 1896.

Application filed December 9, 1895. Serial No. 571,580. (No model.)

To all whom it may concern:

Be it known that I, JOHN STAUNTON KING, of the city of Toronto, in the county of York, in the Province of Ontario, Canada, have invented certain new and useful Improvements in Ventilated Boots, of which the following is a specification.

My invention relates to improvements in ventilated boots and shoes; and the object of the invention is to provide an improved means whereby the shoe may not only be thoroughly ventilated, but also prevented from squeaking without deleteriously affecting the external appearance or internal construction of the boot or shoe; and it consists essentially in making merely a central passage-way provided with perforations underneath the inner sole and through the center of the filling, the forward end of the passage-way being bounded by narrow strips and having a soft filling of a composition of rubber and ground leather at each side of these strips, while the rear end of the passage-way is connected to a concavo-convex outwardly and upwardly flaring casing provided with a bent lower end and a recessed rib forming two passage-ways, the ends of the passage-ways being connected to the outer air by two eyelet-holes, one on each side of the central seam, as hereinafter more particularly explained.

Figure 1 is a perspective bottom view of a boot constructed in accordance with my invention, the sole and heel being removed and portions of the boot being broken away to exhibit the construction. Fig. 2 is an end view of the back of the boot, showing the position of my ventilating-casing in dotted lines. Fig. 3 is a longitudinal section through the boot through the zigzag lines $x' x^2 y' y^2$, Fig. 2. Fig. 4 is a cross-section from the vamp and sole. Fig. 5 is a detail of the ventilating heel-casing. Fig. 6 is another view of this casing.

In the drawings like letters of reference indicate corresponding parts in each figure.

A is the upper of the boot, which is turned inwardly upon the inner sole at a and has the welt B sewed around the edge, as shown.

C C is the filling next the heel, which is formed in two parts, divided so as to form a channel D. The channel D extends from the filling forwardly to the toe of the shoe, being bounded from the front end of the filling C C

by the side strips C' C'. Between the strips C' C' and the welt B on both sides of the channel D, I provide a soft moist filling C of a mixture of rubber cement and ground leather. When the sole is put on, this mixture is kept in a moist condition. Heretofore in boots provided with a ventilating-channel the great difficulty has been the squeaking of the boots; but by providing this soft filling between the side strips of the channel and the welt the squeaking is entirely prevented.

The channel D is provided with a series of perforations d, which are made larger toward the heel of the boot and smaller toward the toe, with no perforations at all underneath the portion where the ball of the foot would rest. Formerly the perforations were arranged continuously along the channel, and upon the bending of the foot the ball of the foot would press against the perforations, and the edge of the perforations would make the boot uncomfortable for walking. By leaving the perforations out at this point and making them smaller toward the toe no inconvenience in this way is experienced.

E is a casing, preferably of metal, formed of the front plate, E', and the rear plate, E², both of which are substantially concavo-convex. The casing E is arranged behind the counter F of the shoe, between such counter and the outer leather or upper. The lower ends of the portions E' and E² are bent forwardly, and the portions are suitably connected together around their edges. The rear plate, E², has a grooved rib e extending from the top to the bottom, where it gradually merges into the concavo-convex form. This rib serves to divide the passage-way into two halves, and also, being grooved, provides for the reception of the back seam of the upper, so that the outer side of the seam is maintained even with the contour of the heel. The upper end of the plate E² is beveled downwardly, as shown, so as to provide for the insertion of the eyelets G, one on each side of the seam, so as to provide for the passage of the air into the channel. Above the eyelets, between the lining and the upper, I provide a filling-strip a', so as to preserve the contour of the heel portion. I also provide a strip a² beneath the bottom of the casing E and between it and the outer leather or upper.

In order to hold the undeturned portion of the upper down flat beneath the bent end e' , I provide a thread or cord H , which I pass through the abutting edges of the bottom seam, so as to bind them together and hold them down and pass the ends of the threads or cords through the inner sole A' , the ends of these threads being held in said sole by the contraction of the same about the threads to when the needle by which the threads are passed through the sole is withdrawn. (See Figs. 1 and 3.) These threads or cords are provided, as no nails could be passed into the edge, as the bent end e' would interfere. The sole A^2 and heel A^3 are secured on the outside of the welt and heel portion in the usual manner.

By the construction such as I have described the outside portion of the boot is not deleteriously affected, as the eyelet-holes are very neat, being placed one on each side of the seam. The seam is also preserved flat, so as to conform to the contour of the back of the heel, and the squeaking is effectually prevented.

What I claim as my invention is—

1. In a ventilated boot or shoe the combination with the sole and heel and inner sole and filling, of a central channel in the filling extending from the toe to the heel and provided with perforations extending through the inner sole and a back casing comprising substantially concavo-convex outwardly and upwardly flaring plates suitably connected together and having bent forward ends to connect with the channel, the back plate being beveled downwardly, and eyelet-holes made in the heel portion on each side of the seam as and for the purpose specified.
2. In a ventilated boot or shoe the combination with the sole and heel and inner sole and filling, of a central channel in the filling extending from the toe to the heel and provided with perforations extending through the inner sole, and a back casing comprising substantially concavo-convex outwardly and

upwardly flaring plates suitably connected together and having bent forward ends to connect with the channel, the back plate being beveled downwardly, and a grooved rib dividing the casing centrally into two passage-ways and forming a seat for the seam, and eyelet-holes one on each side of the heel as and for the purpose specified.

3. In a ventilated boot or shoe the combination with the sole and heel and inner sole and filling, of a central channel in the filling extending from the toe to the heel and provided with perforations extending through the inner sole and a back casing comprising substantially concavo-convex outwardly and upwardly flaring plates suitably connected together and having bent forward ends to connect with the channel, the back plate being beveled downwardly and eyelet-holes made in the heel portion on each side of the seam and a filling above the eyelet-holes between the lining and the outer leather as and for the purpose specified.

4. In a ventilated boot or shoe the combination with the sole and heel and inner sole and filling, of a central channel in the filling arranged as specified, an end casing connected with the channel and a thread H extending through the bottom turned-in edges of the abutting seam, and the inner sole as and for the purpose specified.

5. In a ventilated boot or shoe the combination with the sole and heel and inner sole and filling, of the back divided solid filling forming one portion of the channel and the side strips extending forwardly from the front end of the solid divided filling and forming the toe portion of the channel and the soft moist flexible filling extending between the side strips of the toe portion of the channel and the welt as and for the purpose specified.

JOHN STAUNTON KING.
